WARD N. GERE, OF SYRACUSE, NEW YORK, ASSIGNOR, BY MESNE ASSIGNMENTS, TO ECLIPSE TEXTILE DEVICES INCORPORATED, OF ELMIRA HEIGHTS, NEW YORK, A CORPORATION OF NEW YORK

METHOD AND APPARATUS FOR PERFORATING THE CORES OF YARN PACKAGES

Application filed September 21, 1926. Serial No. 136,808.

This invention relates to a method and apparatus for perforating the cores of yarn packages.

Yarn is usually wound on a tubular core 5 of thick paper or pasteboard, and, in order to produce spot-coloring of the yarn by the methods described in U. S. Patent No. 1,724,015, of Ward N. Gere, dated August 13, 1929, and U. S. Reissue Patent No. 17,096 10 of James S. Johnston, dated October 2, 1928, and for other purposes, it is desirable to provide the paper core with a series of relatively small perforations so that the coloring fluid may be introduced from the inside of 15 the cone outwardly through said perforations and into the registering portions of the yarn, or from the periphery inwardly by suction.

Provision has heretofore been made for 20 perforating these paper cones with the yarn thereon from the inside outwardly but under this practice relatively small portions or burrs of the paper are forced into and against the adjacent inner layers of the yarn which it has been found interfere more or less with 25 the free unwinding of these inner layers of the yarn from the paper cone.

On the other hand, it has been proposed to 30 perforate the paper cones from the exterior inwardly to avoid the objections above referred to but under these conditions it has been necessary to unwind the yarn from the paper cone before the perforations could be formed.

The main object of the present invention is 35 to provide a simple and efficient means for perforating the paper cones from the exterior inwardly without unwinding the yarn therefrom thereby not only avoiding the objectionable peripheral burrs but also effecting a more 40 or less loosening of the portion of the yarn registering with the perforations in the paper core so that the coloring fluid may pass more freely and uniformly through the portions of the yarn registering with the perforations either from the periphery of the 45 yarn inwardly or from the inside of the paper core outwardly according to the method employed in the spot coloring operation.

Another object is to reduce the time and 50 labor required for the perforating and col-

oring operations and thereby to greatly increase the output of the spot colored yarn on the cones.

Other objects and uses relating to specific parts of the apparatus will be brought out in 55 the following description.

In the drawings:—

Figures 1 and 2 are opposite side elevations of a machine for carrying out the objects stated, a portion of Figure 2 being taken in 60 the plane of line 2—2, Figure 3.

Figure 3 is a vertical sectional view taken on line 3—3, Figure 1.

As illustrated, the yarn cone as —A— upon its paper supporting core or cone —a— is 65 placed upon a suitable mandrel —1— which in this instance is detachably secured by screw connections with one end of a shaft —2— so as to be able to rotate with said shaft about a horizontal axis although it is 70 evident that the mandrel may be otherwise supported if desired.

The shaft —2— is journaled in suitable bearings on a main supporting frame —3— and together with the mandrel is adapted to 75 be rotated intermittently for effecting a similar intermittent rotation of the yarn cone A and its supporting cone —a—.

The frame —3— is provided on one side with an upright guide-way —4— for receiving, supporting and guiding a vertically movable cross head or plunger —5— which, in this instance, overhangs the periphery of the 80 yarn cone —A— but may be otherwise supported for reciprocatory movement toward and from said periphery.

The cross head —5— is provided with a plurality of, in this instance, two sets of punches —6— arranged in spaced relation lengthwise of and preferably radial to the axis of the 85 mandrel —1— between the ends thereof and also between the ends of the yarn cone —A— and its paper core —a— when the latter are mounted upon the mandrel.

As clearly shown in Fig. 3 each of the 90 punches 6 is a cylindrical rod which has a length greater than the radial depth of the yarn mass —A— and has a blunt rounded front end. I have found that an instrument of this character displaces the threads of the 95 100

5 yarn mass when forced into the mass so that it may penetrate the mass without cutting, tearing or in any way injuring the yarn. At the same time, its blunt round point is capable of penetrating and perforating the pasteboard core —a.

10 The portions of the mandrel registering with the punches —6— are provided with annular grooves —7— into which the inner ends 10 of the punches —6— are adapted to project when operated to perforate the yarn cone —A— and its paper cone —a—, the remaining portions of the mandrel being preferably conical and of a diameter corresponding 15 to the inner diameter of the portions of the paper cone —a— with which they are adapted to engage for supporting said paper cone —a— and yarn cone —A— co-axial with the mandrel —1— and shaft —2— and also 20 for frictionally engaging the inner surface of the paper cone —a— for transmitting rotary motion from the mandrel to the paper cone and thence by friction to the yarn cone.

25 The cross head —5— with the plungers —6— thereon is reciprocally movable vertically toward and from the periphery of the yarn cone —A— for forcing the punches —6— through the registering portions of the 30 yarn and also through the registering portions of the paper cone —A— when moved toward the cone while the reverse or upward movement of the cross head serves to withdraw the punches from and some distance beyond the periphery of the yarn cone to allow 35 the perforated paper cone with the yarn thereon to be withdrawn and replaced by an unperforated cone in succession.

40 The means for reciprocating the cross head —5— along the guide-way —4— comprises in this instance a horizontal rotary shaft —8— journaled in a suitable bearing in the upper end of the frame —3— and having one end provided with a crank arm —9— which is connected by a pitman —10— to the 45 cross head —5—, the throw of the crank arm —9— being sufficient to carry the punches —6— entirely through the yarn cone —A— and its paper cone —a—, it being understood that the punches —6— are of sufficient length 50 to pass entirely through one side of the yarn and its paper cone when the lower face of the cross head is engaged with the periphery of the yarn cone —A—.

55 This shaft —8— may be rotated by any suitable means but is preferably provided with a pulley —11— adapted to be belted to any available source of power, not shown.

60 Suitable means is provided for adjusting the mandrel —1— with the yarn cone —A— and its core —a— thereon angularly at each return upward movement of the cross head —5— and its punches —6— so that the punches may enter different portions of the 65 yarn —A— and its core —a— at each downward movement.

For this latter purpose the shaft —8— is provided with a cam collar —12— tight thereon and equipped with a cam tooth —13— for engaging and operating a superposed lever —14— once at each revolution or 70 at each return upward movement of the cross head —5—.

One end of the lever —14— is pivoted at 75 —15— to the upper portion of the frame —3— at one side of the shaft —8— while its other end is connected to the upper end of a downwardly extending pawl —16— having its lower end formed with a tooth —17— adapted to successively engage the teeth of a ratchet wheel —18— which is secured to a 80 corresponding end of the mandrel supporting shaft —2— as shown more clearly in Figure 2.

The free end of the pawl —16— is yieldingly held against the teeth of the ratchet 85 wheel —18— by means of a coiled spring —19—.

A spring detent —20— serves to frictionally hold the ratchet wheel —18— against 90 backward movement and undue rotary movement by the action of the pawl —16—.

The lever —14— is provided with a cam tooth —14'— adapted to be engaged by the cam tooth —13— on the shaft —8— for operating the pawl —16— to rotate the 95 ratchet wheel —18— one toothed space and thereby to effect a similar angular movement of the mandrel —1— and yarn cone —A— and its core —a—.

The cam teeth —13— and —14'— are relatively arranged to cause an abrupt lifting and return of the pawl —16— while the cross head —5— is elevated to the extreme limit of its upward stroke and in the construction shown the cam tooth —13— projects 100 from the shaft —8— in substantially the same direction as the crank arm —9— to assure successive angular movements of the yarn cone at each rotation of the shaft —8— and while the punches —6— are elevated out of engagement with the yarn cone as shown by dotted lines in Figure 3.

Immediately following each angular adjustment of the yarn cone and its core —a— the cross head —5— is forced downwardly 110 to cause its punches —6— to pass radially through the registering portion of the yarn cone —A— and its core —a— so that its points project into the angular grooves —7— in the mandrel —1—.

If any burrs are formed on the paper cone —a— by forcing the punches —6— therethrough they will be on the inside of the paper cone and not on the outside which latter will be perfectly smooth except for the perforations and will allow the inner layers of 115 yarn to be freely unwound from the periphery of the paper cone when necessary.

120 It will be readily understood from the foregoing description taken in connection 125

with the drawings that the yarn cone —A— and its core —a— will be rotated intermittently one tooth space of the ratchet wheel —18— at the end of each upward movement 5 of the punches —6— for successively registering different peripheral portions of the yarn cone and its core —a— with the punches to be perforated by said punches at each downward or inward movement thereof until at 10 the end of each complete revolution of the yarn cone it, together with the core —a— will be perforated at regular intervals throughout its periphery.

When the yarn cone —A— and its core 15 —a— have been perforated in the manner described the coloring matter may be passed through the perforations by the means shown in my pending applications previously referred to or by any suitable means not necessary to herein illustrate or describe for producing the desired spot coloring of the yarn. 20

Although I have shown and described a simple and highly efficient apparatus for carrying out the object of this invention it 25 is evident that other mechanisms may be employed for carrying out the same object, and, therefore, I do not wish to limit myself to this construction.

What I claim is:—

30 1. The method of perforating the core of a wound mass of yarn without unwinding the yarn from the core, which comprises displacing the threads of the mass to provide a passage from the outer surface of the mass 35 to its inner surface, breaking in the portion of the core at the end of said passage by an instrument introduced through the passage, and withdrawing the instrument to permit the passage to close over the perforation which has been formed in the core. 40

2. Apparatus for perforating the core of wound mass of yarn, comprising a mandrel constructed and arranged to receive a core having a mass of yarn wound thereon and 45 formed to provide a free space adjacent to the inner surface of the core at an intermediate part thereof, a rod having a rounded blunt end and having a length greater than the radial depth of the mass of yarn, and 50 means for reciprocating said rod lengthwise to move its front end between a point outside the outer periphery of the mass and a point inside said free space within the inner surface of the core.

55 3. Apparatus for perforating the core of a wound mass of yarn, comprising a mandrel constructed and arranged to receive a core having a mass of yarn wound thereon and having an annular groove, a punch having a 60 rounded blunt front end, and means for moving said punch lengthwise to bring its front end from a point outside the periphery of the mass to a point in said annular groove.

4. Apparatus for perforating the core of 65 a wound mass of yarn, comprising a mandrel

constructed and arranged to receive a core having a mass of yarn wound thereon, a punch having a blunt rounded end, means for reciprocating said punch to move its rounded end between a point outside the periphery of the mass of yarn and a point inside the core of the mass, and means automatically actuated by said reciprocatory means for turning said support about the axis of the mass when the punch is outside 70 the periphery of the mass. 75

In witness whereof I have hereunto set my hand this 16th day of September, 1926.
